UNITED STATES PATENT OFFICE.

WATSON F. QUINBY, OF WILMINGTON, DELAWARE.

TWO-WHEELED VEHICLE.

SPECIFICATION forming part of Letters Patent No. 350,992, dated October 19, 1896.

Application filed July 23, 1886. Serial No. 208,569. (No model.)

To all whom it may concern:

Be it known that I, WATSON F. QUINBY, a citizen of the United States, residing at Wilmington, in the county of New Castle and State 5 of Delaware, have invented certain new and useful Improvements in Vehicles; and I do declare the following to be a full, clear, and exact description of the invention, such as will enable others skilled in the art to which it 10 appertains to make and use the same, reference being had to the accompanying drawings, and to the letters and figures of reference marked thereon, which form a part of this specification.

15 This invention relates to two-wheeled vehicles or sulkies; and it consists in an improved spring-connection between the wheel-axle and shafts and the vehicle-body. The shafts are rigidly connected to the wheel-axle, and upright frames are erected on the shafts above the axle, from which the vehicle-body is suspended by spiral or coiled springs. The 20 springs are attached to the upright frames on each side at a single point only, so that the vehicle-body is free to swing to any extent, the result being that the body always assumes a horizontal position irrespective of the position of the shafts. Check-straps are provided, which are connected to the axle and to the 25 bottom of the body, to prevent the latter from being thrown forward and its lateral movement.

The invention is illustrated in the accompanying drawings, in which Figure 1 is a side 30 view of the vehicle; Fig. 2, a plan view of the same; Fig. 3, a rear view of one of the upright frames, and Fig. 4 a bottom view showing the arrangement of the check-straps.

A is the axle; B B, the wheels, and C C the 35 shafts, which are rigidly connected to the axle and extend behind the same. Forward and back of the axle the shafts are connected by cross-bars D D, and the latter are also connected by longitudinal bars E E, parallel with 40 and close to the shafts. The upright frames F F are attached to and supported by the shafts and longitudinal bars. Each upright frame consists of four upwardly-extending strips, a a b b, and a horizontal strip, c, supported by said strips at their upper ends. The 45 two strips a a are attached to the longitudinal

bar, and are inclined vertically toward each other, but are not inclined laterally. The two strips b b, which are attached to the shaft, not only incline toward each other, but also toward the strips a a. 55

G is the vehicle-body, of any desired construction, being shown as having a floor, d, dash-board e, and seat f. When the vehicle is in use, the floor of the body is just above the plane of the shafts, and the body is suspended within the frames F F and between the cross-bars D D. The body is suspended from the cross-strips c c of the upright frames on each side by coiled or spiral springs H H. There 60 are two of these springs on each side, which are both connected to a single shackle attached to the center of the cross strip c directly above the axle. These springs are inclined away from each other, and are connected to 65 the floor of the vehicle-body some distance apart on either side of the axle. By thus suspending the body it is brought as close as possible to the axle, so that it is subject to the minimum amount of movement due to the 70 ordinary incidents of the movements of the horse and the inequalities of the road, and being suspended from a single point on either side, the floor of the body always assumes a horizontal position irrespective of the position 75 of the shafts, so that even if the shafts rested on the ground the body would remain horizontal. The springs themselves prevent the jarring and jolting from being transmitted to the vehicle-body. 85

To prevent the vehicle-body from swinging laterally beyond reasonable limits, side check-straps, I I, are provided. These straps are secured to the center of the axle, and pass through eyes at the sides of the floor of the 90 vehicle. To prevent the vehicle-body being tilted forward, a similar back check-strap, J, is provided, which is secured to the center of the axle and to the back of the vehicle-body. The several check-straps can be shortened or 95 lengthened, as desired, to regulate the extent of movement. These check-straps may be made more or less elastic, if so desired.

Although the method of suspending vehicle-bodies herein described is more particularly 100 adapted and designed for two-wheeled vehicles, it is not intended to limit the scope of

the invention to such adaptation. The same method of suspending the body above the axles can also be utilized in four-wheeled vehicles, railway-carriages, and the like.

5. I claim as my invention—

1. Upright frames on each side of a vehicle, in combination with the vehicle-body suspended therefrom by coiled springs, said springs being connected to the frames on either side at a single point, substantially as set forth.
2. The axle of a vehicle, the shafts secured rigidly thereto, and upright frames supported by and upon said shafts, in combination with the vehicle-body suspended from said upright frames, said springs being connected to the frames on either side at a single point, substantially as set forth.
3. The axle of a vehicle, the shafts rigidly secured thereto, longitudinal bars parallel with and close to said shafts, and upright

frames supported by said shafts and longitudinal bars, each frame consisting of vertically extending strips attached to said shafts and bars, and a cross horizontal strip connecting the vertical strips, in combination with the vehicle-body suspended from said horizontal strips, substantially as set forth.

4. The axle and shafts of a vehicle, upright frames supported by said shafts, and a vehicle-body suspended from a single point on each upright frame by coiled springs, in combination with a back check-strap connected to the axle and to the rear of the vehicle-body, substantially as set forth.

In testimony whereof I affix my signature in presence of two witnesses.

WATSON F. QUINBY.
